ELECTRIC SWITCH

Allen M. Rossmann, Wilmette, Ill.

Application January 21, 1938, Serial No. 186,177

22 Claims. (Cl. 200—162)

This invention relates to electric switches in general and, more particularly, to switches of high current carrying capacity. In its more particular aspects the present invention is primarily concerned with the construction of the switch blade or movable current carrying and contact making part of the switch.

In switches of high current carrying capacity it is important that the engagement between the blade and the contact stud be under considerable pressure. Switches have been constructed wherein the engagement is along a number of lines or points, as distinguished from surface engagement, attempts being made to maintain the lines of contact or engagement at the requisite pressure. It is one of the objects of the present invention to provide a switch of the above type wherein the pressure of engagement will be along a number of lines or points, with a certainty that the pressure or loss of pressure on any line or point will not substantially affect the pressure along an adjacent or other line or point of engagement.

It is a further object of the present invention to provide a switch the blade of which may be fabricated in a simple manner without requiring special tools or dies and requiring no machining or substantially no machining, and which will nevertheless assure a proper pressure engagement between the blade and the switch stud or studs along a predetermined number of lines or points. In the preferred embodiment of this invention the blade is in the form of a plurality of wires clamped or otherwise secured together in such a manner that the natural resiliency of the wires may be relied upon to exert the necessary pressure against the contact stud or studs. Great strength and a high degree of resiliency may be obtained by using wires each of which comprises a copper jacket and a core of steel, bronze, or other high strength elastic material. In those structures wherein a non-magnetic core must be used I may use bronze, non-magnetic steel, or the like. The copper jacket may be physically united with the core, or the wire may be formed by inserting a rod into a copper tube and then bending the two together to the required shape. By this arrangement the proportions of copper to core may be of any desired ratio. After the composite wire has been bent to the desired shape, the ends of the same may be tinned with solder to prevent exposing the core to atmospheric conditions. The portion of the wire jacket that is in actual engagement with the contact stud, or that actually forms an

electric contact making surface may be coated with silver to increase the conductivity at the contact making points or lines. This may be done by any of the processes known in the art.

The wires may be bent to any shape required for the blade member. In a simple switch the blade may comprise two wires adapted to embrace the switch studs, which wires are drawn together intermediate the ends and spread apart by the contact stud or studs, the arrangement being such that the natural resiliency of the wire will maintain the same in firm pressure engagement with the studs. Where current carrying capacity in excess of that of the two wires is required a larger number of wires may be used. The wires may be bent into various shapes, such as hairpin shape, by way of example, and nested together to form the blade member. In other cases an entire blade may be formed from a single wire bent back and forth to form a number of conducting paths between the contact studs of the switch.

It is an object of the present invention to provide a switch blade of the above mentioned character wherein each individual conductor makes contact with one or both switch studs, and the pressure between each conductor and the stud is predetermined, and is applied in such a manner that neither wear nor change in temperature will have any appreciable effect on the pressure. Furthermore, the accidental displacement of any single conductor can have no effect on modifying the contact pressures of the remaining conductors.

It is another object of the present invention to provide an arrangement wherein each switch blade comprises a plurality of conductors which come into engagement with the contact stud successively during the switch closing operation and wherein the respective conductors of the blade are flexed slightly in progressive sequence to give a definite pressure of each conductor against the stud. Because of the progressive flexing, single pole switches may be assembled and put directly into service without requiring adjustments to obtain proper pressures between the contacting surfaces. Because of the progressive sequence of flexing of the parts or wires of a switch blade the amount of force required to push a blade into proper engagement with its contact stud is substantially reduced.

It is a still further object of the present invention to provide an improved holding means for wires assembled to form a switch blade of the above mentioned character. The holding means

may be constructed to maintain the wires in engagement with the contact stud about which they pivot and prevent retraction of the wires from the stud when the switch is open, and to maintain the individual wires in proper pressure engagement with both switch contact studs bridged by the wires when the switch is closed.

It is a still further object of the present invention to provide a tilting insulator type switch with a switch blade comprising a plurality of wires wherein the arrangement is such that the blade moves substantially parallel to itself throughout the entire switch opening and switch closing operation. Thus if the switch is mounted with the blade in a horizontal position, the blade is maintained horizontal as it moves from the switch closed to the switch opened position, and vice versa. This permits the mounting of suitable sleet hoods over the entire blade structure in a simple manner if the switch is mounted outdoors. Likewise, this construction permits the mounting of a switch of this type in a compartment of a metal-clad switchgear, for instance of the type shown in my patent application Serial No. 160,519, without requiring an excessively large compartment. It is a further object of this invention to provide such a rocking insulator type of switch wherein the blade itself is so shaped as to produce the above mentioned type of motion. It is a still further object of the present invention to provide a switch of this type with a wire type blade wherein the blade itself is so shaped as to produce the above mentioned type of motion. It is a still further object of the present invention to provide a switch of this type with a wire type blade wherein the blade is so constructed that after the switch has moved a short distance in its switch opening operation the pressure between the wire blades and contact studs will be substantially reduced, thus reducing the force required for switch opening operation. Conversely, during the switch closing operation there will be substantially no pressure between the blade and the studs until the switch has moved almost to its fully closed position, when the blade fully grips both studs under pressure. This gripping action is effected by bringing about a resilient spreading of the wires constituting the blade. The wires may thus act as a shock absorber for reducing the momentum of the movable parts immediately preceding full switch closure, at the same time utilizing this momentum to bring the switch parts into proper pressure engagement.

It is a further object of this invention to provide a means for holding wire or similar contact making members of a switch in such a manner as to increase the creepage distance between the holding means and the live parts of the switch. This is particularly applicable to oil circuit breakers or the like, where compactness is essential.

The attainment of the above and further objects of the present invention will be apparent from the following specification taken in conjunction with the accompanying drawings forming a part thereof.

In the drawings:

Figure 1 is a sectional view of a lever switch constructed in accordance with the teachings of the present invention, said view being taken along the line 1—1 of Figure 2 and looking in the direction of the arrows;

Figure 33 is a plan view of still another form of switch blade for a high voltage disconnecting switch;

Figure 34 is a sectional view taken along the line 34—34 of Figure 33;

Figures 35 and 36 are, respectively, front and side views of still another lever switch embodying the present invention;

Figures 37 and 38 are, respectively, front and

side views of still another lever switch embodying the principles of the present invention;

Figures 39 and 40 are, respectively, plan and elevational views of the contact making end of still another switch blade embodying the principles of the present invention;

Figures 41 and 42 are, respectively, plan and elevational views illustrating the present invention as applied to a rocking insulator type of disconnecting switch;

Figure 43 is a view illustrating the switch of Figure 42 in its open position;

Figure 44 is a fragmentary sectional view taken along the line 44-44 of Figure 42;

Figure 45 is a longitudinal sectional view through another type of disconnected switch embodying the present invention;

Figure 46 is a transverse sectional view taken along the line 46-46 of Figure 45;

Figure 47 is a fragmentary sectional view taken along the line 47-47 of Figure 45;

Figure 48 is a sectional view taken along the line 48-48 of Figure 49 and illustrating the present invention as applied to the contact making means of a circuit breaker;

Figure 49 is an elevational view of the circuit breaker contact breaking means of Figure 48;

Figure 50 is a sectional view taken along the line 50-50 of Figure 48;

Figure 51 is a diagrammatic sectional view through a circuit breaker having a contact making mechanism such as is shown in Figures 48-50;

Figure 52 is a front elevational view of another form of circuit breaker contact making means embodying the present invention;

Figure 53 is a sectional view taken along the line 53-53 of Figure 52;

Figure 54 is an end view of the contact making mechanism of Figure 52;

Figures 55 and 56 illustrate alternate means of arranging the contact making wires for a circuit breaker of larger current carrying capacity than that of Figure 52;

Figure 57 is a plan view of the wires of another form of contact making bridging bar of a circuit breaker; and

Figure 58 is a side elevational view of the wires of Figure 57.

In the accompanying drawings similar reference numerals indicate similar parts throughout.

Reference may now be had more particularly to the lever switch shown in Figures 1 and 2. The switch comprises the usual form of support or base 1, of insulating material, on which are mounted contact studs 2 and 3 that are connected at the rear side of the base to line conductors 4 and 5, and are adapted to be interconnected at the forward side of the base by means of the switch blade of the present invention. The contact studs 2 and 3 are preferably cylindrical or oval in cross section, thereby facilitating the making of point contact with the members of the switch blade, although it is to be understood that they may be of any other cross sectional shape whereby line contact instead of point contact is obtained. The stud 3 comprises a hinge stud for the switch blade, and for that purpose is provided with a hinge pin 7 that extends through the stud and projects outwardly at the opposite ends thereof. The blade pivots about the hinge pin 7.

The blade comprises two similar groups of U-shaped or hairpin-shaped wires 10 and 11 adapted to embrace the opposite sides of the contact

studs. The groups of wires 10 and 11 are of similar construction. Each group comprises a plurality of long, narrow, U-shaped or hairpin-shaped wires nestled together, with the two groups secured between the arms 12 and 13 of a U-shaped yoke or bracket of non-magnetic material. The arms 12 and 13 are joined by a bight portion 14. The arms 12 and 13 with the groups of wires 10 and 11 on the inner sides of the arms are secured together by means of a spacer block 16 and three bolts 17 located about midway between the studs, which firmly clamp the groups of wires 10 and 11 between the arms 12 and 13. The hinge pin 7 extends through the nested groups of hairpin wires 10 and 11 and through the arms 12 and 13 so that the pin constitutes a hinge for the arms 12 and 13 thereby permitting turning but preventing longitudinal or lateral shifting of the arms on the pin 7. The lower edge of each of the arms 12 and 13 is bent inwardly to form a short ledge 19 against which the curved portion 20 of the outermost hairpin-shaped wire of each group bears. It is thus apparent that each of the hairpin-shaped wires is extended through the space between the pin 7 and the ledge 19 whereby the groups of hairpin shaped wires are free to rotate about the pin 7 with the U-shaped bracket but cannot slide lengthwise of the arms 12 and 13 thereof. The bight portion 14 of the U-shaped bracket has an insulating handle 22 bolted or otherwise rigidly secured thereto but spaced from the bight portion 14 by a disc 23 of wood or other insulation.

The distance between the groups of wires 10 and 11, at the spacer 16, is somewhat less than the diameter of the studs 2 and 3. The ends of the wires are flexible so that they embrace the studs, being flexed by the studs out of their normal position. The arms 12 and 13 of the U-shaped bracket are sufficiently spaced from the ends of the wires to permit such flexing of the wires by the studs 2 and 3. It is therefore apparent that the individual wires maintain a pressure engagement with the studs 2 and 3 due to their own resiliency. In order that the wires may maintain a very high pressure against the studs the wires are preferably made to include material of a high degree of elasticity whereby a large force is required to produce a small deflection. This is obtained, as will be pointed out as this description proceeds, by making each wire in the form of a tube of copper or other metal of high conductivity reenforced by an internal rod or tube of other material of greater elasticity than copper, such as alloy steel, or bronze or other non-magnetic material of high elasticity.

The forward end of the contact stud 2 is, preferably, of a conical shape whereby the same serves to guide the switch blade into proper position during the switch closing operation. As the switch is being closed the wires 25, 26, 27, etc. engage the stud in succession, and are successively flexed outwardly thereby. By reason of the successive flexing action on the wires, instead of a simultaneous action on all of the wires the amount of force required to effect a switch closing operation is materially reduced.

The individual hairpin shaped wires constituting the group of wires 10 or 11 are free of the arms 12 and 13 of the yoke except at the center, where they are clamped between the arms. By reason of this arrangement a high degree of flexibility is obtained at the contact making ends of the wires or loops, each wire being independently flexible at each of the two studs.

In order to maintain a low contact resistance between the wires and the studs the wires as well as the studs may have a plating of silver, or a silver compound in the form of a wide line at the place of engagement between the wires and the studs. The silver coating or plating may be applied in a manner well known in the art.

From the description above given it is apparent that each individual conductor makes contact with both studs, and it is also apparent that the pressure between each conductor and each stud is predetermined and is applied in such a manner that neither wear nor change in temperature will have any appreciable effect in changing its value. Furthermore, the switch may be assembled with a greater or lesser number of wires as determined by the required current carrying capacity of the switch, without appreciable alterations in the switch design. The spacing block 16 determines the spacing between the two blade members midway between the studs and thus determines the pressure of engagement with the studs. The width of the spacing block is such that as the blade members come down on the opposite sides of the contact stud 2 successive conductors, as they ride on the contact stud, are bowed out slightly, in a progressive sequence. The extent of bowing is predetermined by the spacer block to give the requisite pressure of each conductor against the stud. Because of this feature single pole switches of this construction can be put into service as soon as they are assembled, without first having to undergo adjustments to obtain proper pressures between the contacting surfaces. The force for opening or closing the switch is always applied to the blades approximately midway between the contact studs thereby affording resiliency of action. However, if desired, the actuating handle may be connected adjacent the stud 2, as would be desirable with switches having longer switch blades. Under such conditions two spacing blocks corresponding to the block 16 are used, each located adjacent to but spaced from one of the studs 2-3, and the plates 12 and 13 terminate adjacent the stud 2, separate plates being provided adjacent the stud 3. Such a construction is illustrated in the switch of Figures 7 and 8 to which reference will presently be made.

Multipole lever switches are made by interconnecting two or more single pole switches with a cross bar of insulating material. By making the U-shaped member of each pole, to which the cross bar is attached, of sufficiently light material to permit a small amount of lateral flexure, or by making a loose connection between each U-shaped member and its corresponding switch blade, or by a combination of both measures, each pole can, if desired, be "floated" to make it automatically self aligning with its corresponding contact stud.

Reference may now be had more particularly to Figures 3 and 4 wherein I show one method of making the wire assemblies 10 and 11 for the switch of Figures 1 and 2. For this purpose there is provided a plate or template 30 having a pair of pins 31-32 secured thereto and projecting outwardly therefrom. The pins are threaded to receive nuts 33-34 at their outer ends, and are adapted to support a cover plate 35. One end of a wire is placed at 36, midway between the pins, and the wire is looped around the pin 32 and then back around the pin 31, being wound continuously, and successively around the two pins, until the desired number

of loops or turns have been obtained, in this instance three complete turns. The end of the wire is then clipped off at 37, so that the ends 36 and 37 are both located on the same side of the longitudinal center line between the pins 31-32 and midway between the pins. Thereafter the plate 35 is removed and the bent wire assembly is removed and cut along the center line 38 to form two similar blade halves, one half constituting the wire assembly 10 and the other half constituting the wire assembly 11.

In Figures 5 and 6 I have shown enlarged sectional views of the end of the wire for forming the switch blades. The wire consists of an outer tube or jacket 40 of copper or other metal of high conductivity into which is inserted a wire 41 which may be of steel. On switches of high current carrying capacity it is preferable that the wire core 41 be of non-magnetic material. A non-magnetic steel alloy, such as, for instance, stainless steel or manganese steel may be used. Also, the core 41 may be of bronze or other alloy having great strength and elasticity. The core 41 may comprise a solid rod inserted into the tube 40, or it may itself comprise a tube inserted into the tube 40. After the composite wire has been bent into shape the core 41 cannot be withdrawn from the jacket 40, and no special means need be provided for retaining the core in the jacket. If desired, and when the core is made of non-magnetic material, such as stainless steel or bronze, as mentioned above, the wire including the jacket 40 and the core 41 may be formed and drawn as one integral wire so that the jacket is welded to the core throughout the entire surfaces of contact between the jacket and the core.

By forming the composite wire in the manner above set forth it is possible with a jacket of a given cross sectional area to insert either a solid or a tubular core and thereby obtain a wire wherein the ratio of copper to steel, or the ratio of jacket to core, is of any desired value. In those instances where the core may be affected by weather conditions, or wherein the core is hollow, the ends of each wire of the switch may be sealed by means of a coating of solder or the like, indicated at 43. In the section illustrated in Figures 5 and 6 I have shown the end of a wire wherein there is a maximum ratio of steel to copper for a jacket of this size. If a lower ratio of steel to copper is desired, for the same cross sectional area of copper, the core is made tubular instead of solid.

Reference may now be had more particularly to the switch illustrated in Figures 7, 8, 9, 10 and 11. This switch comprises the usual grounded base 50 having stationary insulators 51-52 mounted thereon which carry contact studs 53-54, each terminating in a line receiving lug 55. In this switch the contact stud 53 is of a circular cross section whereas the stud 54 is of an oval cross section, as is apparent from Figure 8. In this switch, as in the switch previously described, the blade also comprises two similar groups of wires, indicated at 57 and 58. The group of wires 57 is formed in substantially the manner illustrated in Figures 3 and 4, that is, by winding a wire of the type illustrated in Figures 5 and 6 about two pins to form a continuous loop of several turns. In this instance, however, the ends of the wire 59 terminate at an end of the loop instead of at the center of the loop, as is illustrated in Figure 13. In Figure 13 both ends of the wire 59 terminate at the

same end of the loop. They may, however, terminate at opposite ends if desired. The blade halves 57 and 58 are bent so that when assembled together they will form a truss, as illustrated in Figure 8. Adjacent their forward ends the blade halves 57-58 are secured together in definite spaced relationship by a spacer block 61 which is of slightly lesser width than the contact stud 53. Three bolts 62 and a like number of nuts, secure the forward ends of the switch blade sections 57-58 together on opposite sides of the spacer block 61. Between the spacer block 61 and the free ends of the loops 57-58 the individual wire portions of the blade are freely flexible. A U-shaped clip or yoke 65 loosely embraces the free ends of the loops of wires 57 and 58, being bolted to the blade by the bolts 62. The ends of the wires are free to flex towards and away from the arms of the U-shaped clip 65. The clip is sufficiently wide to permit the wires to be flexed outwardly by the contact stud 53 without limitation by the sides of the clip opposite the contact stud. A lock 67 forming also an eye for a switch operating pull rod is mounted at the forward end of the blade in a manner which will be set forth more fully as this description proceeds.

The opposite ends of the blades 57-58 are hinged to swing about a pin 70 that extends through the stud 54. For this purpose the ends of the blade portions 57-58 are secured together in spaced relationship by two strips 71-72, three spacer tubes 73-73-73, short plate-like clips 74-74, and bolts 75, that extend through the clips 74, the strips 71-72 and the spacer tube 73, all as is illustrated more fully in Figure 12. The tubes 73 secure the wires of the blade portions 57-58 a distance apart slightly less than the width of the contact stud 54 whereby the stud flexes the free ends of the wire outwardly a small amount, and by that flexing produces the necessary high pressure between the wires and the stud. The clips 74 are hinged to the stud 54 by the pin 70 so that the clip may rotate about the pin but cannot move radially thereof. The ends of the clips 74-74 are bent inwardly, as indicated at 77 in Figure 8, and thus hold the wire blade against movement radially of the pin 70.

From the description thus far given it is apparent that the switch blade of Figures 7 and 8 may be swung about the pivot 70 to establish or disestablish electrical connections between the contact studs 53-54. As the blade approaches its switch closed position it may engage the outwardly flared ends of guiding tubes 78-78 which serve to guide the blade into engagement with the contact stud 53. The upper end of the contact stud 53 is conically tapered so that if the apex thereof comes between the blades it will guide the blades into proper position.

As the successive wires engage the contact stud 53 they are flexed outwardly, successively, since the diameter of the contact stud 53 is slightly greater than the normal distance between the ends of the switch blade members 57-58 when the switch is in its open position. Due to the successive flexing of the individual wires of each blade member, the force required for the closing operation is substantially less than would be required if each blade were flexed outwardly, as a unit.

In order to prevent the switch from being blown open by the magnetic forces produced during short circuiting conditions, a lock 67 is pro-

vided, which lock is of a construction such as is illustrated more fully in Figures 9, 10 and 11, to which reference may now be had. The lock comprises two similar latch members 81 and 82 pivoted about a spacer 83 on a pivoted pin 84 that extends between the switch blade members and through the U-shaped clip 65. The blade members have a limited amount of permissible flexing movement longitudinally of the axis of the pivoted pin 84 by means of short cylindrical blocks 85. The latch member 81 includes a horizontal portion 88 and a downwardly extending portion 89 which, together with the similar parts 88' and 89' of the latch member 82 form an eye for receiving the end of the switch pole stick for operating the switch. The parts 88 and 89 and the corresponding parts 88' and 89' are of a channel cross section. The parts 88-89' form a housing 90 for a spring 91 which is secured at one end to the part 89 and at the other end to the part 89' and thus serves to draw the latch parts about the pivot 84 into the position illustrated in Figure 10. In this position the latches 81-82 are in the extreme position to which they can be urged by the spring, said latches bearing against the front or right portion 93 of the clip 65. When the end of a switch stick is inserted into the eye formed by the arms of the latch and is pushed or pulled to force the end of the switch blade away from the stud 53, it first engages the horizontal portion 88 of the latch 81 and thus swings the latch clockwise about the pivot 84, thereby bringing the hook of the latch out of engagement with the base of a conical collar 94 secured on the stud 53, and moves the latch until it engages the portion 95 of the opposite latch member. Thereafter further clockwise swinging of the latch 81 about the pivot 84 is prevented. The collar 94 constitutes an anchor for the locking device, and during the switch closing operation acts as a switch stop. Continued movement of the switch stick thereupon forces the switch blade out of engagement with the contact stud 53. The latch 82 is provided only for the purpose of latching the switch in its opposite extreme position if the switch is a double throw switch, that is, provided with a contact structure analogous to the contact 53, but located to be engaged by the blade when the blade is in a position 90 degrees or 180 degrees from the position illustrated in Figure 7.

The blade structure of the switch of Figures 7 and 8 is appreciably wider at its pivoted end than at its other end, as may be seen in Figure 8. This produces a truss effect, strengthening the switch blade against being swayed or twisted out of a position of alignment with the contact studs 53-54.

Reference may now be had more particularly to the switch illustrated in Figures 14, 15, 16 and 17. In this switch, each of the blade members is formed of a single length of wire of the kind illustrated in Figures 5 and 6, bent into a continuous loop similar to the construction illustrated in Figure 13, but differing therefrom, however, in that here the inner end of each wire loop is curled to form almost a complete circle, indicated at 101, to form a bearing for the blade. In this switch, the two-blade members 102 and 103 are pivoted about a pivot pin 104 that extends through a contact stud 105, said pin extending through the loops 101 of the blade members 102-103. By this arrangement I dispense with the plates 74-74 of Figure 8. The two-blade members are spaced apart by a spacer 106 which is of slightly lesser thickness than the thickness

of the stud 105, and are firmly clamped on opposite sides of the spacer 106 by clamps 107-107 and four bolts 108. Since the spacer 106 is slightly thinner than the stud 105, it is apparent that the stud 105 will spread the ends of the two switch blade members, and that the blade members will thereby exert a pressure against the stud 105 by reason of this spreading action. The amount of pressure exerted by the individual wire portions of the blades will be determined by the amount of spread of the wire portions and by the construction of the wires. By changing the ratio of the steel or bronze core to the copper jacket, I may obtain any desired degree of resiliency or elasticity of the end of the blade.

The blade parts 102-103 engage a contact stud 110 and are secured together adjacent to, but spaced from the contact making end of the blades, by clamping means substantially similar to that adjacent the pivoted end of the blades, as illustrated in Figures 16 and 17. The clamping means adjacent the contact making end of the blade differs from the other clamping means primarily in that at the spacer corresponding to the spacer 106 an eye 111 is formed therein for receiving the end of a switch-operating stick. The spacer between the blade members at the contact making end of the blade is of lesser thickness than the thickness of the contact stud 110, so that the contact stud spreads the blade members 102-103 somewhat, thereby producing the required degree of pressure of the blades against the stud. The contact making edges of the wires of this blade may be plated with silver or other metal having a higher conductivity than that of copper, which plating may also be applied to the engaged portions of the studs 105 and 110.

As may be seen from the cross section of Figure 16, the wires of the blades are arranged in four groups forming the corners of a rectangle. At the clamping means, the bolts 108 hold the wires against relative movement in any direction. It is known that the magnetic forces produced as an accompaniment of the flow of alternating current tend to force the current outwardly from the center of the conductor. In a switch of the present construction, if the blade is considered as a conductor, it is to be noted that the center of the blade is hollow, that is, there is a space 112 between the opposite groups of contacting paths of each blade member. By reason of this arrangement, the copper is placed at the corners of a rectangle, where it is of maximum effect in carrying the current, as distinguished from a solid blade construction.

Reference may now be had more particularly to the switch illustrated in Figures 18 to 21 inclusive. This switch comprises an insulating base 120 to which is suitably secured a pair of contact studs 121 and 122 that are adapted to be bridged by the blade. The contact studs are of similar construction, each comprising a wide block having a V-shaped contact-making edge 123. The blade of this switch comprises a group of wires of the construction illustrated in Figures 5 and 6, secured to a bracket comprising non-magnetic side plates 124-125 hinged about the pivot 126 on a standard 127 secured to the insulating base 120. The side plates 124-125 have a pair of clamping plates 128-129 extending between them at their upper ends, which plates form a V-shaped groove, as may be seen in Figure 21, within which the individual wires 130 are clamped. Each wire 130 has a bulge 131 therein (Fig. 22), and the clamping plate 128 has a pro-

jecting portion that fits into the bulge 131, whereas the plate 129 has a circular cavity into which the bulge 131 of the wire fits. The clamping plates 128-129 are firmly clamped between the side plates 124-125 by means of bolts 133, which bolts also serve to clamp a U-shaped saddle 134 in place.

The contact stud 121 carries two wire conductors 135 that support a copper arcing stud 136 and a carbon arcing stud 137. The clamping member 129 carries a flat resilient copper bar 138 that has a copper arcing stud 139 at the end thereof, cooperating with the stud 136. The side rails or plates 124 and 125 support a pair of wires 140, of the construction illustrated in Figures 5 and 6, that are looped around the bight portion of the saddle 134, as indicated at 141, and carry a carbon contact stud 142 at their remote ends cooperating with the contact stud 137. A copper braid or other flexible conductor 143 connects the stud 122 with the wire 140, and through the side plates 124-125 with the conductor 138 and wires 130.

To open the switch of Figures 18 to 20 the side plates 124-125 are caused to swing about the pivot 126 in a clockwise direction. Any standard mechanism for swinging the plates may be provided. The wires 130 are thus separated from the studs 121-122. This, however, does not result in an interruption of the circuit because the arcing contacts 136-139 and 137-142 are still in engagement. Upon further switch opening movement, the studs 136-139 first open, thus shunting the entire circuit to the carbon arcing contacts 137-142. Upon further switch opening movement, the bight of the saddle 134 engages the loop 141 of the wire 140 and forces the contact stud 142 out of engagement with the stud 137, thus interrupting the circuit. By this arrangement, it is apparent that the arc is taken primarily at the carbon contacts 137-142 and secondarily at the arcing contacts 136-139.

The wires 130 and 140 are preferably of a construction such as was previously described, viz: a copper jacket around a core of ordinary steel or non-magnetic stainless steel, bronze or the like, the core being separate from the jacket, or integrally united therewith, as desired. The contact-making edges of the wires 130 may be silver plated, if desired, as may also the contact-making edges of the studs 121-122.

In the switch of Figures 18 to 20 inclusive, each of the wires of the blade 130 is held at its center and is free to flex at its ends. The flexing of each wire is independent of the flexing of the others, and the flexing of the one end of a wire is independent of the flexing of the opposite end. By this arrangement the individual wires may each be adjusted so that each maintains a proper pressure at contacts 121 and 122. The U-shaped edges of the contacts 121-122 permit engagement with a wiping action.

In Figures 23 and 24 I have illustrated how a switch of a construction like that of Figures 18 to 20 may be made for a larger current carrying capacity than is provided by the switch of Figures 18-20. In this arrangement, the contact studs 121 and 122 are each provided with a similar stud 121' and 122' of the same shape, but somewhat longer, than the corresponding studs 121 and 122. In addition to the set of wires 130, in V-shaped formation, there is another set 130' of a similar construction and similarly clamped in place, which set of wires bridge the studs 121'-122'. A V-shaped spacer 146 is interposed

between the clamping plates 128 and 129, said spacing plate being adapted to fit over the projections 131 on the wires 130 and to fit into like projections on the wires 130'. In other respects the switch of Figures 23 and 24 is identical with that of Figures 18-20, and is provided with arcing contacts like that at 136-139 and 137-142 of the switch in Figures 18-20. The wires are of a similar construction previously described. Upon the initial switch opening operation, the wires 130 and 130' will both be moved out of engagement with the contact studs, leaving the arcing function to be performed as heretofore described.

In Figure 25 I have illustrated a lever switch similar to that of Figures 1 and 2 and differing therefrom primarily in that here the arms 12 and 13 of the U-shaped holding bracket retain the wires against longitudinal movement in a somewhat different manner. Here the inturned flanges 19 of the arms 12 and 13 of the switch of Figures 1 and 2 are omitted. Instead, each of the wires of the blade is provided with dents or protuberances 151 so that the bolts 17 that secure the arms 12-13 and the wire blades together fit into the protuberances at the outermost one of the nested wires. By this arrangement, longitudinal movement of the nested set of hairpin wires is prevented. In other respects, this switch is identical with the switch of Figures 1 and 2, and a further description at this time is deemed unnecessary.

Instead of providing the wires of the switch blade with the dents or protuberances 151, the individual wires may be curved to provide a loop 153 (Fig. 26) for receiving the pin 7 of the contact stud. The other wires have loops 154 exceeding 180 degrees, each extending around the loop of the next inner wire. The loop 153 through which the pin 7 extends, together with the loops 154 prevent longitudinal movement of the blade in the same manner as do the inturned flanges 19 of the switch of Figures 1 and 2.

In Figure 27 I have illustrated still another manner of holding the switch blade members against longitudinal movement. This is accomplished by bending the inner wire 155 to provide a loop 156 similar to the loop 153 for receiving the pin 7, and providing the inner hairpin wire 155 with an additional loop 157 for receiving one of the bolts 17 that clamp the arms 12-13 together. By this arrangement the inner hairpin wire 155 will be held against longitudinal movement. The succeeding hairpin loop wires 158 are bent to provide an enlarged portion 159 embracing loops 156-157, whereby the succeeding hairpin wires 158 are also held against longitudinal movement. The switch blade such as is illustrated in Figure 27 may be assembled in a switch such as is illustrated in Figures 1 and 2, or Figure 25, whereby the inturned flanges 19 of the arms 12-13 of Figure 1 may be omitted.

In Figure 28 I show still another arrangement whereby the pin 7 and the bolts 17 may lock the switch blade against longitudinal movement without resorting to the inturned flange 19, in a lever switch such as is shown in Figures 1 and 2, or Figure 25. In this construction each wire has a dent 151 as in the wires of the blade of Figure 25, and the innermost wire 160 has, in addition, a loop 153 as in the blade of Figure 26. Two switch blades such as are shown in Figure 28 are mounted in a switch such as shown in Figures 1 and 2, whereby the inturned flanges 19-19 may be omitted.

In Figures 29 and 30 there is shown an arrangement whereby two hairpin shaped wires are nested together, each of the hairpin wires being provided with dent portions 131' corresponding to the portions 131 of the wire illustrated in Figure 22. This type of switch blade may be clamped in place by clamping means such as illustrated in Figures 1 and 2.

In Figures 31 and 32 I have illustrated a wire switch blade for a switch of the type shown in Figure 8, but differing therefrom primarily in that here the wires are trussed in two directions. The switch blade comprises two similar parts 57' and 58' mounted in the same manner as the switch of Figures 7 and 8. The outer wire of each blade is bowed outwardly as indicated at 170 and 171. For this purpose there is provided an intermediate clamping member 172 which includes a pair of plates 173 and 174 on opposite sides of each blade part, and suitable spacers 175 between the blades. Bolts extend through the spacers and secure the plates and the blades together. The plates 173 or 174 may have, as an integral part thereof, a spacing block that fits between the wire 170 and the wire 176, and a similar block that fits between the wire 171 and 177, the said blocks serving to maintain the wires 170 and 171 spread apart. This trussed type of construction is desirable for blades of great length, since this blade is of considerable strength against bending in any direction. In other respects this switch is of a construction such as is illustrated in Figures 7 and 8 and therefore a further description thereof is believed to be unnecessary.

In Figures 33 and 34 I illustrate another type of switch blade. This construction comprises four similar wires 180, 181, 182, 183 threaded at their outer ends and secured to a rectangular supporting plate 184, by nuts 185, the wires extending through openings in each corner of the plate 184. The wires taper toward one another from the end 184 to the contact-making end 186 where the four wires are secured together in spaced relationship by means of a spacing block 187, clamping plates 188, and bolts 189. The four ends 190 of the wires 180-183 are adapted to embrace a contact stud or to move between the jaws of a contact stud, and are sufficiently flexible at their ends outwardly of the clamping spacer 187 to permit flexing of the same by the contact stud, whereby the contact-making ends 190 of the wires exert a requisite amount of pressure upon the contact stud. Proper alignment of the four wires 180-183 may be obtained by adjustment of the nuts 185 that thread over the ends of the wires. Suitable flexible braided or other copper wire 192 is clamped or otherwise secured to the respective wires 180-183 to establish good electrical connections with the blade. The supporting plate 184 is mounted for switch operating movement in any desired manner, as for a swinging movement or a combination rectilinear and swinging movement, as is well known in the switch art. Because of the greater spacing of the ends of the wires at the plate 184 than at their contact-making end, this blade constitutes a truss of great strength against bending in any direction.

In Figures 35 and 36 there is shown still another type of switch embodying the principles of the present invention. This switch comprises one continuous length of wire bent to form a contact-making length 201 which is bent around an insulating or insulated stationary circular support 202, as indicated at 203, then bent to extend

along the support at 204, then again around the support 202 as indicated at 205, and then bent to form another length of wire 206 parallel to the length 201. The two lengths 201—206 swing about the support 202 into and out of engagement with switch studs 207 and 208. Suitable clamping means 209 is provided for securing the wires 201—206 together midway between the studs 207—208 and spaced apart a distance slightly less than the diameter of the studs 207—208. When the blade is moved into its switch-closed position the wires are spread apart slightly by the studs, whereby the wires exert the requisite pressure against the studs. Suitable operating means may be secured to the clamping means 209. As shown this comprises a bar 211 extending through a loop or eye 212 in the spacer plate of the clamping means. The wire or tube constituting this switch blade may be of the materials heretofore mentioned, comprising a copper jacket reenforced by a solid strengthening core of metal material having a higher elasticity than copper.

In Figures 37 and 38 there is shown still another type of wire switch blade construction embodying the present invention. In this construction the blade comprises two similar blade members indicated at 215 and 216 pivoted on opposite sides of the contact stud 217 by means of a pin 218 that extends through the stud. The pin 218 extends through a loop in the wires similar to the loop 153 of Figure 26. The two blades are secured together in properly spaced relationship by a clamping member 220 including a blade spacer to which an operating eye 221 may be secured. The switch blades are movable into and out of embracing relationship to the contact clip 222, which is wedge-shaped at its forward end, as indicated at 223, to guide the blades on opposite sides of the clip 222. As the blades move over the clip 222 they are somewhat spread, and the parts 224 of the blades exert the requisite pressure against the stud 222. There is considerable length of wire between the contact-making end of the blade and the clamping member 220, whereby the natural resiliency of the wire is utilized. Each of the wires is of a construction such as was previously described.

In Figures 39 and 40 I have shown the contact-making end of still another switch blade constructed in accordance with the present invention. This switch blade comprises two solid copper blades 230 and 231 secured together in properly spaced relationship by means of a spacer 232, clamping plates 233, and bolts 234. The forward end of each blade 230—231 is slotted along the lines indicated at 235 by means of a series of saw-cuts that extend for an appreciable distance from the contact-making end of the blade. Each strip of copper between adjacent saw-cuts is flexible independently of the others. The forward or contact-making ends of the respective strips are bent toward one another, as indicated at 238, to constitute the contact-making portion of the blade. The blade is movable into and out of engagement with a contact-stud 239 in any desired manner. When the blade is in its switch open position, the distance between the opposite contact-making fingers 238—238 is less than the thickness of the stud 239. As the blade is moved over the stud, the contact fingers are spread, whereby each contact finger exerts its pressure against the stud independently of the other contact fingers. The contact making por-

tions of the fingers, as well as of the stud, may be silver plated.

Reference may now be had more particularly to the switch illustrated in Figures 41, 42 and 43. This switch comprises a grounded channel-shaped base 251 on which are mounted stationary insulators 252 and 253, and a rocking insulator 254, which rocks about a stationary pivot 255. The insulator 252 supports a line terminal 256 having a contact stud 257 adapted to be engaged by the switch blade in a manner to be presently set forth. The insulator 253 supports a terminal 258 having a contact stud 259 engaged by the switch blade in a manner presently set forth.

The switch blade comprises two similar blade members 260—261 clamped together to embrace the contact stud 259, and pivoted at the end of the rocking insulator 254, as will be more fully set forth as this description proceeds. The blade 260 comprises a number of loops of wire, in this instance five, nested together. Each loop includes upper and lower inclined contact-making portions 263—264, a straight or horizontal portion 265, and a circular curved portion 266. The circular portion merges with the horizontal straight portion 265 along a smooth curve 267, and merges with the inclined contact-making portion 264 along a smooth curve 268. The wires of the switch blade 260 are nested together, as illustrated in Figure 42. Adjacent their forward end the blade members 260—261 are secured together, and in properly spaced relation with respect to the stud 257 by means of clamp members 270—270, a spacer 271 and bolts 272. The clamp members are pivoted to the cap of the insulator 154 about the pivotal center 273. The clamps 270 and spacer 271 secure the two switch blades a distance apart slightly less than the diameter of the stud 257.

The blade members 260—261 embrace the stud 259 and are guided in place by means of an upper pin 277 and a lower pin 278 extending through the stud. The horizontal portions 265 of the blades are secured together in properly spaced relationship by means of clamps 280—280 on opposite sides of the blades, a spacer 281, and bolts 282—283. It is to be noted that the clamp 280 is at an angle to the wires of the blade. This angle is so chosen that the length of wire of the innermost loop at 284, between the adjacent bolt 282 and the pin 277 is equal to the length of wire of the outermost loop between the adjacent bolt 283 and the pin 278. By this arrangement the pressure exerted against the stud 259 by the outermost wire of the loop is the same as the pressure exerted against the stud by the innermost wire, as well as by the intermediate wires.

The radius of curvature of the outermost loop at 266 is exactly equal to the radius from the center 255 to the pivot point 273. The center of curvature is indicated at 288. The arcs 266 of each of the inner loops of wires are arcs of circles about the same center 288. This is for a purpose to be presently set forth.

When the insulator 254 is rocked about the center 255 in a clockwise direction to open the switch, it causes the blades 260—261 to move to the right, as seen in Figure 42. As the point 273 rises from the base 251, causing a rise of the switch blade, the right hand end of the blade rises on the pin 278 an exactly equal amount so that the portion 265 of the blade remains horizontal. When the rocking insulator reaches its vertical position, the lowermost part of the arcuate portion 266 is resting on pin 278. Subsequent

turning of the insulator 254 causes the point 273 to follow a circular curve which now approaches the base 251. At the same time, the arcuate portion 266 rides downwardly on the pin 278 an equal distance, so that the portion 265 still remains horizontal. This result is obtained by making the radius of curvature from 288 to the curved portion 266 equal to the radius from 255 to 273, as previously stated, and locating the center 288 in such a position that the four points 278, 255, 273, and 288 constitute the corners of a parallelogram. The switch blade therefore moves always parallel to itself so that the part 265 always remains horizontal when the switch is mounted in the position illustrated in Figure 42.

The contact-making ends of the blades, comprising the straight inclined wire portions 263—264, are outwardly flared at their forward end, as may be seen from Figure 41, to guide the switch blade over the contact stud 257. The respective inclined wire portions 263—264 are flexed outwardly by the contact stud 257, since the diameter of the stud is greater than the width of the spacer 271. Due to this flexing, the respective wires exert a spring pressure against the contact stud when the switch is in its closed position. Likewise, the ends of the blades that are on opposite sides of the stud 259 exert a spring pressure against the stud 259. Current therefore flows from the stud 259, through the upper and lower parts of each blade, to the stud 257. The mean effective length from the stud 259 to the stud 257 over the upper half of the loop is approximately the same as over the lower half of the loop.

As the switch moves to its switch open position, which is illustrated more fully in Figure 43, the blades slide on opposite sides of the stud 259. In order to ease the operation of the switch, it is desirable that the pressure of the blades against the stud 259 should be released after the blades have separated from the opposite stud 257. This is accomplished by forming a slight indentation in each of the wires at its point of engagement with the stud 259, as is illustrated more fully in Figure 44. As may be seen from this figure, each of the wires projects inwardly towards the stud a small amount, as indicated at 290. This amount may be of the magnitude of the order of $\frac{1}{16}$ of an inch. As the switch blade is operated towards its switch closed position, the wires loosely embrace the stud 259 until the forward end of the blade engages the stud 257. At that time, the inward projections 290 engage the stud 259 and thereby exert their pressure against this stud. This acts as a shock absorber tending to reduce the impact of the moving parts against the stud 257 and consequent shock on the insulator 252. During the switch opening operation the reverse action takes place, the pressure of the blades against the stud 259 being released when the blades have moved sufficiently to cause the projections 290 to clear that stud.

Reference may now be had to the switch illustrated in Figure 45. This figure shows an isolating switch adapted to be mounted, for instance, in a metal-clad switchgear of the type illustrated in my pending application, Serial No. 117,827, filed December 28, 1936, although it is to be understood that this switch may be used in other connections, wherever desired. The contact-making mechanism is mounted in a tube 301 of porcelain or other insulation. The tube extends through a hole in a metal wall 302 of the switchgear and is

bolted in place by a ring 303 cemented to the tube and bolted to the wall 302. At the forward end of the tube 301 there is cemented or otherwise secured a copper ring 305 having an integral closure 306 through which is threaded a switch stud 307, suitably secured in place. The forward end of the stud 307 is square for receiving conductors suitably clamped thereto, and is hollow to facilitate cooling. At the rear end of the tube 301 there is mounted a short tube 310, of copper or the like, which is cemented or otherwise secured within the porcelain tube 301. The tube 310 has a lug 311 projecting therefrom for receiving line connections. The switch blade for establishing connections between the stud 307 and the tube or terminal 310 comprises a series of wires 312, in this instance sixteen in number, secured together in assembled relation at the center of the wires, with each wire being free of all the others at both ends, and for the entire length of the wire from the center. The wires are, preferably, composite wires of the type shown in Figures 5 and 6. Each wire has an inwardly bent portion 313 at the center thereof. The wires are assembled on the inside of a copper or other ring 314 that has an internal peripheral projection 315 that extends into the bent portions 313 of the wires. Thereafter a pair of circular discs 316 and 317 are inserted into the tube formed by the sixteen wires and are clamped together by extending a bolt 318 through the discs 316 and 317, and then tightening a nut at the end of the bolt. When the discs 316—317 are drawn together by tightening of the nut, the wires are forced outwardly and rigidly clamped between the discs and the ring 314. A clevis 320 is pivotally mounted on the end of the bolt, and has an insulating operating rod 321 secured thereto. By pulling or pushing on the rod 321 the blade which comprises the wire assembly may be moved longitudinally within the insulating tube 301.

Each of the wires has an inwardly bent protuberance 322 at its forward end, which engages the contact stud 307 forming a point of contact therewith. Each of the wires 312 is bent at its rear end into a hook formation and extends over the rear of the tube 310, as indicated at 325. Each hook portion has an inwardly bent projection 326 that makes contact with the outside of the tube 310. The tube 310 is preferably, although not necessarily, beveled at its rear end, as indicated at 327, to facilitate guiding of the contact making portion 326 over the outside of the tube when the switch blade assembly is moved to its switch closed position. The inside diameters of the circles formed by the contact making points 322 and 326 of the respective wires are somewhat less than the outside diameter of the stud 307 and the ring or tube 310, respectively, so that the individual wires are flexed outwardly at the contact making edges. This causes the wires to exert sufficient pressure to maintain good electrical connections. The contact making points may be silver plated, if desired.

In Figure 45 I have shown the switch in its closed position, and have also shown, in dotted lines, the position of the rear end of the blade when the switch is open. The operating rod 321 may extend through a hole in a metal wall 70 330 of the switchgear, and is pulled to its open position by any suitable mechanism, for instance, such as is disclosed in my pending application, Serial No. 117,827, above referred to.

While the switch illustrated in Figure 45 is one supported within a tubular insulator, being

particularly applicable to installations wherein there is provided a grounded or other apertured barrier between the lines or buses, the invention is not limited to such an arrangement. For instance, in my application Serial No. 160,519, filed August 23, 1937, I show a disconnecting switch wherein the contact studs or equivalent terminals are mounted on spaced vertically extending insulators and wherein the switch blade is movable horizontally into and out of its switch closed position. Obviously the switch blade illustrated in Figure 45 is applicable to such a switch. In such a switch the rings 305 and 310 would be supported on parallel spaced vertically extending insulators and the wire assembly comprising the switch blade would be movable between those rings in exactly the same manner as is illustrated in Figure 45. When the switch is moved towards its open position and the wires leave the contact stud 307 then in such a switch there is no insulator corresponding to the insulator 301 for guiding the blade in its horizontal movement. Under those circumstances, the ring 310 is made of somewhat greater length so that this ring serves to maintain the wire switch blade assembly in horizontal position when the wires leave the contact stud 307. The mode of operation of such switch would be exactly the same as of the switch illustrated in Figure 45, since the major difference would be as to the means used for supporting the rings 305 and 310.

Reference may now be had to Figures 48 to 51 inclusive, showing the principles of the present invention as applied to a circuit breaker. The circuit breaker itself is indicated diagrammatically in Figure 51, and comprises a head 340 to which is secured a depending tank 341 of metal, having the usual cylindrical insulating liner 342. Insulating bushings 343 and 344 extend through the head 340 into the tank, and end in switch terminals 345—346 that are adapted to be bridged by the contact-making mechanism to be presently described. The contact-making mechanism comprises a U-shaped bridging member 348 supported by two metal rods 349 that extend into the circuit breaker head, and are adapted to be moved downwardly to lower the bridging member and interrupt the circuit. When the bridging member moves downwardly it draws two arcs, one at the contact 345 and the other at the contact 346. The contact 345 is in an enclosed chamber 356 filled with oil and devoid of any gases or other readily compressible media. This chamber communicates through an outlet 351 in an insulating plate 352 with the part of the circuit breaker wherein there is formed the arc at the contact 346. The oil or other insulating liquid in this chamber extends above the bottom of an insulating plate 353 which constitutes the top of the chamber 356. A suitable insulating plate or barrier 354 extends between the insulating barriers 352 and 353. The bubble of gas formed at the arc 345 forces oil from the chamber 356, through the opening 351 into the chamber 357, which is open at the top to the space below the top of the circuit breaker head. The oil thus set into motion and flowing through the opening 351 tends to cool and blow out the arc formed at contact 346, thus interrupting the circuit.

Reference may now be had to Figures 48 to 50 showing the switch blade construction. In these figures I have shown the invention as applied to a three-phase circuit breaker within a single tank. The three phases are indicated at A, B and C of Figure 48. Since the contact-making struc-

ture 348 is the same for each phase, a description for one phase will be sufficient. Each bridging member comprises two groups of U-shaped wires 369—361, of the type illustrated in Figures 5 and 6, clamped on opposite sides of an insulating bar 362, but spaced from the bar by spacer plates 363. Suitable clamping plates 364 on opposite sides of the bridging members clamp the bridging members against the spacer plates 363 and firmly secure the same to the insulating bar 362. The arms of the outermost U-shaped wire of each bridging member are of a somewhat greater length than the remaining wires, as indicated at 366, to serve for arcing purposes. Upper and lower transverse beams 367 and 368 firmly secure the three insulating bars of the three phases together. The two operating rods 349—349 extend through the transverse beams 367—368 and clamp the beams together into firm gripping relationship to the insulating bars 362 by means of upper and lower clamping nuts 369, and suitable spacers 370. By this arrangement, the operating rods 349 not only support the beams 367—368, but serve also to clamp them in rigid gripping relation to the insulating bars 362 that support the respective bridging members.

It is to be noted that bight portions 373 of the bridging members are spaced from the insulating bars 362. This arrangement is provided in order to increase the creepage distance between the operating rods 349 and the bridging members. As may be seen from Figures 48 and 50, the creepage distance from the rod 349 to the bridging member extends along the beam 367 or 368 to the insulating bar 362 and then along the insulating bar 362 to the spacer 363 and then along the spacer to the bridging member. This creepage distance affords adequate insulation between live parts and the metal rods 349 located between adjacent phases.

The wires constituting the bridging members 348 are of a construction such as was previously described, namely, a copper tube with an internal reinforcement of metal of higher elasticity than copper. The inner core may be welded to the copper jacket throughout the area of contact between the two, or may be separate therefrom. The wires constituting the bridging member are individually flexed outwardly by the contacts 345—346, and by that flexing are caused to exert the necessary pressure against the contacts. It is to be noted that the lower end of each contact stud 346 is tapered. Thus as the wires ride on the contact studs they are progressively flexed outwardly, thereby easing the closing operation by acting as a spring cushion against shock.

Reference may now be had to the switch illustrated in Figures 52, 53 and 54. In this circuit breaker, the contact-making wires are of exactly the same construction as in the circuit breaker of Figures 48—50. The support for the wires and the rest of the bridging members are different. In this instance the two groups of nested U-shaped wires of each phase are clamped in spaced relationship by tubular spacers 380, clamping plates 381—382 and bolts 383. The bight portions of the U-shaped bridging members are secured in spaced relationship at their center by blocks 384 that receive an insulating operating rod 385 between them, and rectangular clamping plates 386. In this construction the operating rod must be of insulation, and there is one operating rod for each phase of the circuit breaker. In other respects,

this circuit breaker may be the same as that previously described.

If the circuit breaker of Figures 52-54 is to be of larger current-carrying capacity than that allowed by the two sets of U-shaped wire assemblies 360-361, two additional sets of U-shaped wire assemblies 390 and 391 of a construction the same as that of the assemblies 360 and 361 may be provided. This is illustrated in Figure 55. These wire assemblies are spaced from the assemblies 360-361 by short spacers 392, and rectangular plates 386', which correspond, respectively, to the spacers 382 and plates 386. The assemblies are secured together by bolts 383', which correspond to the bolts 383 of the circuit breaker previously described, except that they are longer. In this construction, the bridging member for each phase is slightly wider than in the circuit breaker previously described. The arm portions of the U-shaped bridging members 390 and 391 are somewhat longer than those of the bridging members 360 and 361. The contact 346', which corresponds to the contact 346 of Figure 54, is somewhat wider and it includes two additional contact-making edges 393, and additional tapered surfaces 394 for guiding the bridging members 390-391 in position. In this construction the arcing extension 366 on the outermost wire of the bridging assemblies 360 and 361 may be omitted and the corresponding arcing arrangement provided on the corresponding U-shaped wire of the assemblies 390 and 391. In other respects, this construction is the same as that previously described.

It is to be noted that the addition of the two wire assemblies 390-391 to the switch of Figure 52, necessarily increases the over-all height of the switch, since the contact point 393 is above the corresponding contact edge 395. If an increase in height is to be avoided, the increased capacity may be obtained by a greater increase in the width of the contact structure. This is illustrated in Figure 56, wherein the additional bridging members 390' and 391' are of the same height as the bridging members 360 and 361. Here, however, the contact structure 397 must be of greater width than the contact 346' in order to permit the contacting edges 398-398 to be located at the same horizontal level as are the contacting edges 395. The wire assembly 390' is secured between clamping plates 382 at the sides and central clamping plates 386 spaced from the corresponding plates on opposite sides of the assembly 361 by tubular spacers 380' and 393, respectively. Bolts, corresponding to the bolts 383 and 383', but somewhat longer, secure the assembly together.

In Figures 57 and 58 I have illustrated still another form of bridging member for a circuit breaker. This bridging member comprises an assembly of wires 401 and an assembly of wires 402 adapted to be secured together at their center portion 403 in spaced relationship with an insulating operating rod extending through the center portions 403. The ends 406 of the contact-making wires are free of one another and freely flexible, the contact-making wires being secured together only at their center portion 403. The contact-making ends 406 are adapted to be moved into and out of engagement with a contact stud similar to the stud 346. However, the contact stud for this type of switch blade has a contact-making edge which extends in a vertical direction rather than a horizontal direction. The wires constituting this switch blade are of

a construction such as is illustrated in Figures 5 and 6 heretofore described.

In each of the wire switch blades or contact making parts of the switching structures herein described the wires are of a construction such as is illustrated in Figures 5 and 6, namely, a copper jacket reenforced by a rod or tube of material having a higher elasticity than copper. The reinforcing filler may be ordinary steel, or low magnetic stainless steel or other alloys, or non-magnetic material such as bronze or the like. In those switch blades where the copper itself has the necessary strength and elasticity the internal reenforcing core may be omitted entirely, using either solid or hollow tubular wires or rods. While the wires have been shown as of a circular cross section this is not an indispensable part of the invention, as square or other polygonal shapes may be used. In each of the constructions herein illustrated the individual wires are clamped together at an appreciable distance from the contact making portion of the wire, and each wire is individually flexible and may be bent mechanically independently of each of the others to adjust its normal position so that it will be flexed a sufficient amount by the switch contact stud to cause the wire to maintain the requisite pressure against the stud, regardless of the relative spacings of the wires by the clamping means. In each construction the arrangement is such that if any one of the wires is out of proper position it cannot affect the pressure adjustment of the other wires. This is true whether the misadjusted wire is too far from the contact stud so that it exerts an insufficient or no pressure against the stud, or whether the misadjusted wire is too close to the stud whereby it exerts an excessive pressure against the stud. Furthermore, in each of the switches herein illustrated the blade may be readily assembled from standard lengths of wire, and the parts will require no machining to bring the movable members into proper alignment with the stationary members. The wires are so arranged with respect to the contact studs, that the magnetic forces resulting from the current flow are in such directions as to force the individual wire into firmer pressure engagement with the studs, rather than out of pressure engagement with the studs. Also, in each of these constructions the contact making portions of the blade and of the stud may be silver plated to reduce the contact resistance, without requiring silver plating of the entire wire lengths. By reason of the wire arrangement the switch blades have a large exposed surface area thereby increasing the radiating surface and thus facilitating cooling of the blade.

In compliance with the requirements of the patent statutes I have here shown and described a few preferred embodiments of my invention. It is, however, to be understood that the invention is not limited to the precise constructions here shown, the same being merely illustrative of the principles of the invention. What I consider new and desire to secure by Letters Patent is:

1. A switch blade comprising a plurality of U-shaped wires nested together with at least a portion of one of the U-shaped wires lying between the arms of another U-shaped wire, and means securing the nested wires in assembled relation.
2. A switch blade comprising a plurality of wires in the form of long U-shaped loops nested together with at least a portion of one of the U-shaped wires lying between the arms of another

U-shaped wire, and means securing the U-shaped loops together at the arms thereof.

3. A switch blade comprising a continuous wire wound in the form of a long and comparatively narrow loop of more than one turn with the axis thereof in substantially one plane.

4. A switch blade comprising a plurality of longitudinally extending lengths of wire, the wires being arranged so that in a transverse cross section through the blade they occupy the corners of a hollow polygon, and means for clamping the wires together and holding them against spreading in one direction at right angles to the length of the blade, one of said clamping means comprising also a handle for operating the switch blade.

5. A switch blade comprising a plurality of parallel rows of wires with adjacent wires of a row in contact throughout substantially their entire lengths and means between the ends of the wires securing the wires together in an assembly, both ends of each wire being permitted a limited amount of motion transversely of the rows.

6. A switch comprising a pair of aligned contact members, wire holding means movable from a switch open position to a switch closed position, a plurality of rows of contact wires carried by said means and movable thereby into and out of bridging relation to the contact members, the rows embracing the contacts and the ends of the wires being permitted a limited amount of relative motion transversely of the rows and also in the direction of switch closing movement, and being flexed against their natural resiliency by the contacts, each wire comprising a jacket of substantially copper and a reenforcing core of metal of higher elasticity than copper, whereby flexing of the wire by the contact causes the core to press the jacket in spring pressure engagement with the contact.

7. A switch comprising a pair of spaced contact studs, a plurality of contact making wires movable into and out of bridging relation to said studs, and means for securing the wires together to form a switch blade, said wires being held intermediate their ends by the securing means with one end of at least one of the wires freely flexible in the direction of switch closing movement of the wires, and the ends of the wires being flexed out of position by the studs whereby the wires exert a spring pressure against the studs, the ends of the respective wires being free of one another to permit independent bending of each wire to adjust the pressure of the wires against the studs.

8. A switch comprising a hinge contact stud and another contact stud, a hinge pin at the hinge contact, blade holding means hinged to the hinge pin, a switch handle secured to the holding means, and a switch blade carried by the holding means and comprising a plurality of resilient wires secured to the holding means between the studs and free of the holding means at the ends thereof, said wires bridging the studs and flexed by the studs so that the individual wires exert a spring pressure against the studs, at least one wire being looped around the hinge pin.

9. A switch comprising a hinge contact stud, a hinge pin extending therethrough, a switch blade comprising a plurality of turns of wire looped around the hinge pin and pivoted thereabout, and means for preventing longitudinal movement of the wire with respect to the pin.

10. A switch comprising a hinge contact stud, a hinge pin extending therethrough, a switch blade comprising a plurality of turns of wire looped

around the hinge pin and pivoted thereabout, and means for preventing longitudinal movement of the wire with respect to the pin comprising a member pivoted on the pin and having a projection in the path of attempted longitudinal movement of the wire from the pin.

11. A switch comprising a pair of spaced contact studs, a pair of pivotally mounted members embracing at least one stud and extending towards the other stud but spaced from both studs transversely of the switch, wire blades between the members and the studs and exerting a spring pressure against the studs, the wires comprising the blade being curved and nested together with at least one wire embracing another and the wires being secured together and to the pivotally mounted members at a distance from the studs and being individually flexible at the studs.

12. A switch comprising a pair of spaced contact studs and a blade member movable into and out of engagement with the studs, said blade member comprising a plurality of groups of wires on opposite sides of the studs, the wires in each group being curved and nested together with at least one wire embracing another, the wires extending between the contact studs.

13. A switch comprising a pair of spaced contact studs and a blade member movable into and out of engagement with the studs, said blade member comprising a plurality of groups of wires on opposite sides of the studs, the wires in each group being curved and nested together with at least one wire embracing another, the wires extending between the contact studs, clamping means clamping all of the wires together, said clamping means being spaced from the contact studs, and said wires being individually flexible between the clamping means and the adjacent contact stud.

14. A switch comprising a pair of spaced contact studs and a blade member movable into and out of engagement with the studs, said blade member comprising a plurality of groups of wires on opposite sides of the studs, the wires in each group being curved and nested together with at least one wire embracing another, the wires extending between the contact studs, a yoke embracing the groups of wires, the wires being secured to the yoke intermediate the ends of the wires, the yoke being pivoted at one end thereof and movable for moving the blade to its open and closed positions.

15. A switch including a blade comprising a plurality of lengths of resilient wire extending the full length of the blade, means securing the wires together, said blade being pivoted at one end, a contact stud adapted to be embraced by the free end of the blade, a yoke mounted on and loosely embracing the wires at the free end of the blade, a switch lock pivoted to the blade at the yoke and forming also an eye for a switch actuating rod, said lock comprising two pivoted latch members each forming a part of the eye, and spring means at the portion of the eye furthest from the blade and urging the latch members to their locking positions.

16. A switch comprising a pair of spaced contact studs, a wire movable into and out of bridging relation to the studs, means including a rocking insulator for moving the wire, and means for maintaining the wire substantially parallel to its original position throughout its movement to its alternate position.

17. A switch comprising a pair of spaced contact studs, a wire movable into and out of bridg-

ing relation to the studs, a rocking insulator pivoted between said studs for moving one part of the wire in an arcuate path, means for guiding another part of the wire in a similar arcuate path to maintain the wire substantially parallel to its original position as it moves to its alternate position.

18. A switch comprising a pair of spaced contact studs, a wire movable into and out of bridging relation to the studs, a rocking insulator pivoted between said studs for moving one part of the wire in an arcuate path, means for guiding another part of the wire in a similar arcuate path to maintain the wire substantially parallel to its original position as it moves to its alternate position, said means comprising pin means carried by one of the contact studs and said wire having an arcuate portion guided by the pin means as the wire moves to its alternate position.

19. In a switch, a switch blade comprising a plurality of U-shaped wires nested together with at least a portion of one of the U-shaped wires lying between the arms of another U-shaped wire.

20. In a switch, a switch blade comprising a plurality of wires formed into loops with the ends

of the loops opposite one another and with at least a portion of one of the looped wires embraced by another of the looped wires.

21. A switch comprising a pair of spaced contact studs, a wire movable into and out of bridging relation to the studs, actuating means for moving one part of the wire in an arcuate path to move it into and out of bridging relation to the studs, and means for guiding another part of the wire in a similar arcuate path to maintain the wire substantially parallel to its original position as it moves to its alternate position.

22. A switch comprising a pair of contact studs, a wire movable into and out of bridging relation to the studs, actuating means for moving one part of the wire in an arcuate path to move it into and out of bridging relation to the studs, stationary means for guiding another part of the wire in a similar arcuate path to maintain the wire substantially parallel to its original position as it moves to its alternate position, said wire having an arcuate portion guided by the stationary means as the wire moves to its alternate position.
